US0D1071931S

(12) **United States Design Patent** (10) Patent No.: **US D1,071,931 S**
(45) Date of Patent: ** Apr. 22, 2025

(54) **SET-TOP BOX**

(71) Applicant: **SHENZHEN SKYWORTH DIGITAL TECHNOLOGY CO., LTD**, Shenzhen (CN)

(72) Inventor: **Dongsheng Wang**, Shenzhen (CN)

(**) Term: **15 Years**

(21) Appl. No.: **35/520,764**

(22) Filed: **Mar. 4, 2024**

(80) **Hague Agreement Data**

Int. Filing Date: **Mar. 4, 2024**

Int. Reg. No.: **DM/236530**

Int. Reg. Date: **Mar. 4, 2024**

Int. Reg. Pub. Date: **May 3, 2024**

(30) **Foreign Application Priority Data**

Sep. 4, 2023 (CN) 202330571413.5

(51) **LOC (15) Cl.** **14-03**

(52) **U.S. Cl.**

USPC **D14/358**; D14/125

(58) **Field of Classification Search**

USPC D14/230, 233, 234, 235, 236, 237, 238, D14/238.1, 358, 356, 357, 432, 434,

D14/435.1, 496, 425, 239, 125

CPC ... H01Q 1/44; H01Q 9/06; H04B 1/08; H04B 1/38; H04N 5/64; H04N 21/40
